Primary Examiner — Paula Greene(74) *Attorney, Agent, or Firm* — Perkins Coie LLP(57) **CLAIM**

The ornamental design for an interactive sport earbud, as shown and described.

DESCRIPTION

FIG. 1 is a perspective view of an embodiment of an interactive sport earbud showing our design.

FIG. 2 is a front view thereof.

FIG. 3 is a back view thereof.

FIG. 4 is a right side view thereof.

FIG. 5 is a left side view thereof.

FIG. 6 is a top view thereof; and,

FIG. 7 is a bottom view thereof.

Elements identified in broken lines in the accompanying drawings form no part of the claimed invention.
